FACE PANEL FOR A CARD CATALOG DRAWER

Stephen F. McKeon, Parkersburg, W. Va., assignor to
Sperry Rand Corporation, New York, N.Y., a corpora-
tion of Delaware

Filed Mar. 6, 1969, Ser. No. 16,078

Term of patent 14 years

Int. Cl. D6—01

U.S. Cl. D33—1

FIG. 2.

FIG. 1.

FIG. 3.

FIG. 4.

FIG. 1 is a front view of a drawer face panel showing my new design;

FIG. 2 is a side elevational view of the drawer face panel shown in FIG. 1;

FIG. 3 is a top view thereof; and

FIG. 4 is a perspective view thereof.

I claim:

The ornamental design for a face panel for a card catalog drawer, substantially as shown.
